SEPTIC TANK

Harold A. Laswell, 4609 Walden Drive,
Louisville, Ky. 40229

Filed Oct. 9, 1973, Ser. No. 404,685

Term of patent 14 years

Int. Cl. D23—01

U.S. Cl. D23—2

Fig. 1

Fig. 2

Fig. 3

Fig. 4

Fig. 5

Fig. 6

FIG. 1 is a top plan view of a septic tank showing my new design;

FIG. 2 is an elevation view taken from one side thereof, the opposite side being a mirror image of the side shown;

FIG. 3 is a bottom plan view thereof;

FIG. 4 is an elevation view taken from the right side of FIG. 2;

FIG. 5 is an elevational view taken from the left side of FIG. 2; and

FIG. 6 is an enlarged fragmentary view taken on line 6—6 of FIG. 2.

I claim:

The ornamental design for a septic tank, as shown and described.
